UNITED STATES PATENT OFFICE.

CLINTON F. SHADLE, OF INDIANAPOLIS, INDIANA, ASSIGNOR, BY MESNE ASSIGNMENTS, TO INDIANA EQUIPMENT CORPORATION, OF INDIANAPOLIS, INDIANA, A CORPORATION OF INDIANA.

RAMP-RAIL SHOE FOR TRAIN CONTROL.

Application filed January 20, 1923. Serial No. 615,819.

To all whom it may concern:

Be it known that I, CLINTON F. SHADLE, a citizen of the United States, and a resident of Indianapolis, county of Marion, and 5 State of Indiana, have invented a certain new and useful Ramp-Rail Shoe for Train Control; and I do hereby declare that the following is a full, clear, and exact description thereof, reference being had to the accompanying drawings, in which like numerals refer to like parts.

This invention relates to an automatic train control system, and particularly to one of the elements thereof, to wit, a switch construction and the means for actuating the same.

The chief object of the invention is to improve the present switch and actuating shoe therefor, whereby contact will be positively insured between a rail and the shoe, which rail may be of the type associated with the local circuit of a block signal system.

The chief feature of the invention consists 25 in the particular construction and arrangement of the parts of the shoe and of the switch associated therewith and actuated thereby.

The full nature of the invention will be 30 understood from the accompanying drawings and the following description and claims.

In the drawings Fig. 1 is a side elevational view of a truck with the shoe and switch 35 positioned thereon. Fig. 2 is a top plan view of the switch and actuating means therefor with the cover removed. Fig. 3 is a bottom plan view of the shoe construction and support. Fig. 4 is a transverse sectional view of a railway track showing the ramp rail associated therewith and the shoe construction positioned on the rail. Fig. 5 is a front view of the switch-insulated contact support. Fig. 6 is an enlarged side elevational view of the shoe construction with the cover and other parts broken away and sectioned to show still other parts in detail at the instant of engagement with the ramp rail. Fig. 7 is an end elevation of the shoe 45 and switch end with a portion of the shoe in section. Fig. 8 is an end elevation of the shoe construction.

In the drawings, see Figs. 1 and 4, there is illustrated a truck frame 10 having the

truck wheels 11 which ride upon the usual track rails 12 of a railway roadbed. Positioned adjacent and parallel to the rails 12 is a ramp rail support 13 which supports a ramp rail 14 having an inclined approach, and herein illustrated in the form of an angle iron. Associated with the ramp rail and contacting the same is a shoe construction 15, and said shoe construction 15 is suitably supported upon the shoe supporting base 16, which is angular in cross section, 55 and has a face 17 suitably secured to the truck frame 10 by bolts 117 or any desired means and insulated therefrom by means of the insulated bushings 18, see Fig. 7.

Positioned above the supporting plate or base 16 and hingedly supported thereby is a cover 19 which carries a staple 20 and a U-shaped or slotted bracket 21. The base 16 hingedly supports a link 22 having a threaded connection with an adjusting nut 23. The 70 adjusting nut pivotally supports a hasp 24. From the foregoing it will be understood that the hingedly supported cover may be locked in closed position by means of the hasp and staple and may be drawn down 75 tight to form a water-tight connection between said cover and the base, by means of the peripheral groove 25 and the gasket or sealing peripheral member 26. Within said cover and supported by said base is a switch 80 construction, herein to be described in detail and the actuating means for said switch 85 which is associated with a shoe construction.

The shoe construction is shown clearly in Figs. 3, 6, 7 and 8. The base 16 is centrally 90 apertured at 27, and surrounding said aperture upon the under side of said base 16 is a boss 28. Slidably supported in said aperture is a plunger 29, and said plunger terminates in a slot 30 which extends transversely thereof. An elongated box frame 31 on each end is provided with a projection 131 having an elliptical or elongated opening 32 through which the bolt 130 extends. The bolt 130 is received by the slot 30 and is pivotally secured therein by the pin 132. Between the projections 131 and the post 29 are coiled springs 133. The box frame 31 is provided with two pairs of ears 33, and pins 34 extend through said ears and secure to the box frame a cover 35 having a central recess 36.

In each end of the elongated box frame 31, there is supported a pin 41, and each pin

41 supports a roller 42 having a corrugated periphery 43. As shown clearly in Figs. 3, 7 and 8, the corrugations of the two rollers are in staggered relation to each other. The reason for this is shown clearly in Fig. 7. In this figure it will be noted that the two edges of the ramp rail 14 are engaged by two opposite faces of adjacent corrugations and contact is thus secured. The following wheel or roller makes contact upon the top of the ramp rail through the top of one of the corrugations. Difficulty has heretofore been experienced in securing an excellent contact between the ramp rail and the shoe. When ice forms upon the ramp rails, the usual shoes succeed in cutting through the ice to insure relatively good contact, but the shoes which are utilized at the present time cannot penetrate frost and secure good contact. The present construction insures good contact through the edges of the rail and act through the top of the rail, except from the other roller.

Reference will now be had to Figs. 3 and 25 6. In said figures there is illustrated a plate 44 having a cleaning surface 45 complementarily formed, and said plate is positioned intermediate the two rollers and is suitably secured to the box casing so as to simultaneously clean both rollers. It will be remembered that the box frame is pivotally supported by the post 29, and that the post is slidably supported in the base 16. Herein, see particularly Fig. 8, each end of the 30 box frame carries inwardly extending angular links 46, and the pair of links is secured to a rod construction 47 which passes through the base 16 and is concentric with a coiled spring suitably and adjustably secured thereon by means of the several nuts 49. Thus the downward movement of the box frame and post or plunger is not only cushioned but limited as well.

The box frame, see particularly Figs. 3, 45 6 and 8, is provided with forwardly projecting tongues 50 to form a groove 51 at each end thereof. In each groove 51 formed by the projecting tongue 50, there is positioned a T-shaped guide 52 suitably secured 50 to and depending from the base 16. From the foregoing it will be understood that rocking movement of the frame is guided by the guides 52 which also prevent any excessive movement transversely of the rocking movement.

The exterior lower portion of the plunger 29 is cut away to form a pair of oppositely positioned shoulders 53, which shoulders are curved or arcuate and bear upon a hardened 60 plate 54, said plate being supported upon an equalizing spring 55, which spring extends substantially the full length of the box frame and is positioned between the cover 35 and the pins 34 securing the cover to the box 65 frame.

As shown clearly the plunger 29 is hollowed and forms a spring-receiving member 56 in which is positioned a spring 57; said spring 57, as will hereinafter be described, is retained in said plunger 29 and exerts 70 a downward force upon said plunger so as to cause the arcuate faces 53 to bear upon the bearing plate 54 supported by the spring 55, and thus serve to maintain the plunger, and, therefore, the shoe frame in the lowermost position, said position, however, being limited by the chain construction hereinbefore described.

Reference will now be had to Figs. 2, 6 and 7, and in said figures it is noted that a support 58 is suitably secured to the upper side of the base 16, as shown, and said support is apertured at 59 so that the aperture therein registers with the aperture 27 in the base 16 and provides a support for the plunger 29. Extending upwardly and upon opposite sides of the plunger, and preferably at right angles to the arcuate bearing faces 53 are the guides and supports 60 which also extend inwardly towards each other at 61 90 to partially surround the plunger, and thus serve to guide the upper end of the plunger. Said upper extensions also support the pins 62 which secure a transversely extending member 63, and said member 63 is seatable in the hollow portion 56 of the plunger, and the wall of said plunger is oppositely slotted, as at 64, to slidably receive said transversely extending member 63. Extreme upward movement of the shoe and plunger thus may 100 be limited by the engagement of the base of the slot 64 with the transverse member 63. Said transverse member 63 upon the portion that is positioned within the hollow of the plunger carries a spring retainer portion 65, shown most clearly by the dotted lines in Fig. 6, and this spring retainer not only retains the spring within the plunger, but also enables said spring to normally force the shoe into engagement with the ramp rail 14. 110

The plunger extends upwardly between the guides 60 and straddles the transverse member 63. In the upper end, a pin 66 extends transversely of the plunger and substantially parallel to the pin 132. The pin 66 extends through the plunger, and as shown clearly in Figs. 2 and 7, the free end thereof terminates in a ball member 67 receivable by a socket 68 carried by a supporting member 69.

The supporting member 69 is provided with a tongue and groove connection at opposite ends, as at 70, with the upstanding arms 71 of a bracket construction. The 125 slideable member 69 carries an insulated block 72, and said insulated block 72 carries a double and inverted U-shaped contact 73 which consists of three parallel conducting strips, the intermediate parallel conducting strip being longer than either of the two 130

- other strips, and connected to said strips at opposite ends, leaving the free end of each outside strip terminating short of the central strip. The length of said outside strips is 5 such that there is an intermediate overlapping or median position, wherein contact may be made simultaneously with the three strip portions. The upstanding arms 71 of the bracket construction carry a horizontal 10 support 74, and said support 74 is provided with three insulated bushings 75 which slidably support a metallic contact or brush 76, said brush being adapted to engage the aligned contact strip 73. A spring contact 15 finger 77 is suitably secured by the terminal means 78 to the base 16 and is insulated therefrom. Said contact finger 77 is apertured to slidably receive a bolt 79 carried by the transverse support 74 and insulated therefrom. 20 A spring 80 is interposed between said support, and said spring contact 77 and the nuts 81 limit the outward movement of the contact spring finger 77. The details of the switch construction may be modified as desired without departing from the broader 25 features of the invention.

From Fig. 6 it will be noted that the rear roller 42 is slightly larger than the front roller, but said rollers have their centers in 30 the same horizontal plane. The equivalent construction would be to have both rollers of equal size and have the rear roller center positioned slightly below the plane including the front roller center. With either of the 35 aforesaid constructions, the rear roller is the first to engage the ramp rail 14, and thus tip forwardly the frame until the front roller engages the rail. The force of the engagement of the roller with the rail is absorbed by the equalizing spring 55. The 40 normal rail engaging position of the frame or shoe is tilted forwardly very slightly.

The invention claimed is:

1. A rail shoe construction including a 45 supporting frame, and a plurality of peripherally corrugated rollers arranged tandem and supported thereby and adapted to contact with a rail, the corrugations of each roller being staggered with respect to the 50 corrugations of the adjacent roller.

2. A rail shoe construction including a supporting frame, a roller supported thereby and adapted to contact with a rail, and a roll cleaner of a width at least equal to the roller 55 and supported by the frame adjacent the roller.

3. A rail shoe construction including a supporting frame, a pair of rollers supported in tandem thereby, and adapted to contact 60 with a rail, and a roll cleaner supported by the frame intermediate the rollers for simultaneously cleaning both.

4. A rail shoe construction including a supporting frame, a pair of peripherally 65 corrugated rollers supported thereby in tan-

dem and adapted to contact with a rail, and a cleaner complementarily formed and positioned intermediate said rollers for cleaning both.

5. A rail shoe construction including a 70 supporting frame, a pair of peripherally corrugated rollers supported in tandem thereby and adapted to contact with a rail, and a cleaner complementarily formed and positioned intermediate said rollers for 75 cleaning both, the corrugations of each roller being staggered with respect to the corrugations of the adjacent roller.

6. A rail shoe construction including a 80 supporting frame, a peripherally corrugated roller supported thereby and adapted to contact with a rail, and a complementarily formed cleaner supported by the frame adjacent the roller.

7. In a rail shoe support, the combination of a base, a slotted plunger slidably supported thereby, and guide means supported by said base and associated with said slotted plunger.

8. In a rail shoe support, the combination of a base, a hollow plunger slidably supported thereby, a spring in said hollow plunger, and a spring retainer associated with said plunger and supported by the 90 base.

9. In a rail shoe support, the combination of a base, a slotted plunger slidably supported thereby, guide means supported by said base and associated with said slotted plunger, and a stop for engaging said guide 100 means to limit the travel of said plunger.

10. In a rail shoe support, the combination of a base, a hollow plunger slidably supported thereby, a spring in said hollow plunger, a spring retainer associated with 105 said plunger and supported by the base, and a stop for engaging said spring retainer to limit the travel of said plunger.

11. In a rail shoe support, the combination of a base, a hollow and slotted plunger slidably supported thereby, a spring in said plunger, and means supported by said base and associated with said hollow and slotted plunger for guiding the same and retaining the spring.

12. In a rail shoe support, the combination of a base, a hollow and slotted plunger slidably supported thereby, a spring in said plunger, means supported by said base and associated with said hollow and slotted plunger for guiding the same and retaining the spring, and a stop carried by said plunger for engaging said means to limit the travel of said plunger.

13. In a rail shoe construction, a shoe support, a post pivotally and slidably supporting the same, yielding means for maintaining the post in one limiting position, and other yielding means for maintaining the post in the opposite position.

14. A rail shoe construction comprising a support, a shoe frame tiltably supported thereby, a plurality of rollers supported in tandem by said frame upon axes parallel to the frame pivot for successive engagement with a rail, and yielding means for absorbing the shock of said engagement directed parallel to the tandem positioning.

15. A rail shoe construction comprising a support, a shoe frame tiltably supported thereby, a plurality of rollers supported in tandem by said frame, the rear roller projecting lower than the forward roller, whereby said rear roller will first engage the rail and tilt the frame and thereby cause said forward roller to engage the same.

16. A rail shoe construction comprising a support, a shoe frame tiltably supported

thereby, a plurality of rollers supported in tandem by said frame, the rear roller projecting lower than the forward roller, whereby said rear roller will first engage the rail and tilt the frame and thereby cause said forward roller to engage the same, and yielding means for absorbing the shock of said engagement.

17. The combination of a rail with an inclined approach, and a rail shoe construction having a plurality of rollers arranged in tandem and positioned so that the rear roller will engage the inclined portion of the rail prior to engagement by the forward roller.

In witness whereof, I have hereunto affixed my signature.

CLINTON F. SHADLE.
